POTATO DIGGER CHAIN

Fred P. Noffsinger, Robert W. Noffsinger, and
Nelson E. Reynolds, Greeley, Colo.

Application May 4, 1939, Serial No. 271,688

8 Claims. (Cl. 198—195)

This invention relates to a conveyor chain of the bar type and more particularly to the type of chain known as a potato digger chain. On a digger the chain is used as an elevator chain to elevate the dug potatoes and to sift the clods therefrom. On a grader, these chains are used to separate the various sizes of the potatoes in accordance with the spacing of the link bars.

The standard potato digger chain consists of a series of parallel bars bent at their extremities to form hooks which engage the next adjacent bar to provide an endless chain of parallel hooked bars. This construction permits only a very small area of frictional contact between the hooks and the bars which causes the hooks to quickly wear away the bars at the point of contact to rapidly increase the pitch of the chain until the bars break through and the entire chain must be discarded. The wear at this point is still further facilitated by the fact that the digger chains must work in sand and soil which provides a perfect abrasive at the friction points; and also by the fact that since the hooks are formed on the bars, both are of the same type of material, a condition which always facilitates bearing wear.

The principal object of this invention is to provide a digger chain construction which will avoid the above difficulties of the usual chain; which will provide a relatively large contact area at the points of friction; which will eliminate all frictional contacts with the hooks; which will provide a link bearing construction which, when it becomes worn, can be quickly and easily reversed to provide new bearing surface so as to double the life of the chain; to provide a bar construction in which the metallic contacts will be between differing types of metals; and to eliminate all sharp corners or edges which would result in damage to the jackets of the potatoes.

Other objects of the invention are to provide a chain from which any one or more of the links can be quickly and easily removed, without the use of a master link and without dismantling the entire chain, and yet to provide a construction in which it will be impossible for the links to become unhooked while in operation; and to provide a link construction of a type which can be doubled, where exceedingly great strains are imposed, so as to greatly increase the tensional strength of the usual bar chain without increasing the size of the bars.

Other advantages reside in the detail construction of the invention which is designed for greater ultimate economy, greater wearing qualities and less operating trouble than present chains. These

will become more apparent from the following description.

In the following detailed description of the invention reference is had to the accompanying drawings which form a part hereof. Like numerals refer to like parts in all views of the drawings and throughout the description.

In the drawings:

Fig. 1 is a face view of a section of the improved chain. 10

Fig. 2 is an edge view of a section of the improved chain.

Fig. 3 is a side view of one form of bearing spool employed in the invention.

Fig. 4 is a cross section therethrough, taken on the line 4—4, Fig. 3. 15

Fig. 5 shows an outside face of the bearing spool.

Fig. 6 is a detail view illustrating a second form of bearing spool. 20

Fig. 7 is a face view of an alternate form of the chain to be employed where great tensile strength is required.

Fig. 8 is a detail view of the bearing spool employed with the alternate form. 25

Fig. 9 is a cross section therethrough, taken on the line 9—9, Fig. 8.

Fig. 10 is an edge view of the alternate form of the chain illustrating it in position on a typical chain sprocket. 30

The improved chain as shown in the first embodiment consists of a series of bars 10 the extremities of which are both bent to one side and slightly back upon themselves to form inset link portions 11. The link portions 11 are turned back upon themselves to form parallel sided hooks 12. The planes of the hooks are parallel to each other and at right angles to the axis of the bar 10. 35

As thus far described, the chain does not differ materially from the usual digger chain. In the improved chain, however, the hooks are bent on a larger radius than in the usual chain and they are prevented from contacting the surfaces of the adjacent bars by means of bearing spools 13. 40 Each spool has an axial bearing opening 14, of a diameter to rotatably receive a bar 10, and each is surrounded by a peripheral arcuate hook groove 15 for receiving one of the hooks 12. The two sides of each hook 12 are parallel to each other. The groove 15 in each spool is formed in a corresponding shape so as to provide two parallel, straight portions 16 for receiving the straight parallel sides of the hook so as to prevent rotation of the spools in the hooks. The two 45

faces of the spools are rounded back to the hook groove, as illustrated, so that there will be no sharp edges or corners for damaging the jackets of the potatoes.

5 The chain is designed to run over the usual chain shakers and sprockets. The latter engage the bars immediately inside of the spools and the inner faces of the latter are formed larger than the outer faces thereof to protect the hooks 10 from frictional engagement with the sprocket teeth.

In cases where excessive wear is encountered, a sleeve 18 may be projected from the inner face of each spool member, as shown in Fig. 6, to prevent 15 grit from entering between the spool members and the bar and to provide a bearing bushing for engaging the sprocket teeth so as to prevent tooth wear on the bars.

It will be noted that due to the tension of the 20 chain, all of the wear in the bearing opening 14 will be along one side thereof. When this wear has progressed sufficiently to materially increase the pitch of the chain, all of the spool members may be given a one-half turn in their hooks so 25 as to bring the unworn sides of the openings 14 against the bars to restore the chain pitch and to provide double life for the chain. The spools may be released for rotation by simply depressing a link bar from the chain run, as shown at 30 the right in Fig. 2. This allows the depressed spools to be slid upwardly out of their hooks so that they can be easily turned to the new position and replaced.

When the chain is in its normal position, the 35 spool members cannot be removed from their hooks due to the inwardly offset bends in the link portions 11 which causes each link portion to contact the next adjacent hook should any attempt be made to compress the chain for unhooking purposes.

40 In Figs. 7 to 11, a second form of the chain is shown, embodying the same principle but designed for carrying excessive loads. This form of the chain consists of a series of link bars 19, the extremities of which are bent to provide a 45 link portion 20. These portions are then continued to form a double, U-shaped hook 21. From the double hook, the bar extremity is continued back to the straight portion of the bar 50 and is welded thereto, as indicated at 22, to provide a double link portion and double hook on the extremity of each bar. Naturally, this double member will withstand twice the strain of a single member in resisting straightening of 55 the hook and, due to the welded end 22, it forms a closed structure the strength of which exceeds twice that of a single hook.

50 This form of the invention also employs a spool member 23 which surrounds the bar 19 between the sides of the double link member. The spool member is provided with two grooved bosses 24, one adjacent each of its extremities, which rest in the sockets of the hook of the next adjacent bar to prevent rotation of the spool member in 60 the hooks. All rotation is confined to the surfaces between the bars and the spool members.

65 Grooved bosses may be placed on both sides of the spool member as illustrated, if desired to make this spool also reversible for wear.

70 A typical sprocket wheel is indicated at 25 in Fig. 10 with its teeth at 26. It will be noted that the teeth 26 will enter in the outline of the hooked portion of the bars and that the spool members 23 will form bushings on the bars for receiving the thrust and wear of the teeth 26.

In the ordinary chain the pitch increases so rapidly due to wear between the links that soon only one of all the teeth 26 is actually touching the chain. This concentration of load on a single tooth rapidly wears away both the chain and the sprocket, a condition which is avoided by the use of this invention. 5

It is desired to call attention to the fact that the spools and the ends of the hooks are so rounded and recessed that they blend tangentially into each other and no edges or corners are left to break or bruise the potatoes. 10

The first described form of bearing spool is much lighter in weight than the other forms and would thus decrease the entire weight of the 15 chain. This decrease in weight would of course decrease bearing wear so that the shorter spools would probably wear as long as the longer spools.

20 While a specific form of the improvement has been described and illustrated herein, it is desired to be understood that the same may be varied, within the scope of the appended claims, without departing from the spirit of the invention.

Having thus described the invention, what is 25 claimed and desired secured by Letters Patent is:

1. A conveyor chain comprising: a series of link bars; a pair of bearing members mounted on each link bar; a connecting hook formed on each extremity of each bar, each of said hooks engaging a sleeve member on an adjacent bar, said hooks being non-circular; and a corresponding non-circular peripheral surface on said bearing members engaged by said hooks to prevent 35 rotation of the latter on said bearing members.

2. In a conveyor chain of the type having a series of parallel, transversely extending bars terminating in hooks, a pair of bearing members surrounding each bar and receiving the hooks of 40 the next adjacent bar, said bearing members being recessed for the reception of said hooks so as to prevent the bearing members from shifting on said bars.

3. In a conveyor chain of the type having a 45 series of parallel, transversely extending bars terminating in hooks, a pair of bearing members surrounding each bar and receiving the hooks of the next adjacent bar, said bearing members being recessed for the reception of said hooks so 50 as to prevent the bearing members from shifting on said bars, said bearing members being non-circular in cross section at said recesses to prevent rotation of said bearing members in said hooks. 55

4. A conveyor chain comprising: a series of link bars; a pair of spool members mounted on each link bar; a connecting hook formed on each extremity of each bar engaging a spool member on an adjacent bar; and a sleeve formed on and 60 extending inwardly along the bar from each of said spool members for engaging a chain sprocket.

5. A bearing member for digger chains of the bar and hook type comprising: a spool member 65 having an axial passage for the reception of a bar and a peripheral groove for the reception of a hook.

6. A bearing member for digger chains of the bar and hook type comprising: a spool member 70 having an axial passage for the reception of a bar and a peripheral groove for the reception of a hook, the contour of said groove being such as to prevent rotation of said spool member in said hook. 75

7. A link bar for digger chains comprising: a bar, each extremity of each bar being bent to form a double U-shaped hook with the bar extremities returning back to the bar and being secured thereto, adjacent to but spaced from the bent extremities thereof; and bearing sleeves surrounding said bars between the bent extremities and the secured extremities thereof, for receiving the U-shaped hooks of an adjacent bar.
- 10 8. In a conveyor chain of the type having a series of parallel, transversely extending bars

terminating in hooks, a pair of bearing members surrounding each bar and receiving the hooks of the next adjacent bar, said bearing members being recessed for the reception of said hooks so as to prevent the bearing members from shifting on said bars, the extremity of each hook being inclined into the recess of a bearing member so as to expose no sharp edges. 5
